US00D763023S

(12) **United States Design Patent**
Austin, III et al.

(10) **Patent No.:** **US D763,023 S**
(45) **Date of Patent:** **** Aug. 9, 2016**

(54) **SHOWER DOOR DISPLAY**(71) Applicant: **LIBERTY HARDWARE MFG. CORP.**, Winston-Salem, NC (US)(72) Inventors: **James Allen Austin, III**, High Point, NC (US); **Matthew Klein**, Apex, NC (US); **Patrick Boehnen**, Summerfield, NC (US); **Laura Hawkins**, Madison, NC (US)(73) Assignee: **LIBERTY HARDWARE MFG. CORP.**, Winston-Salem, NC (US)(***) Term: **14 Years**(21) Appl. No.: **29/480,761**(22) Filed: **Jan. 29, 2014**(51) LOC (10) Cl. .... **06-06**(52) U.S. Cl. USPC .... **D6/683.1**(58) **Field of Classification Search**USPC D6/672, 673, 678, 678.1, 678.3, 678.4, D6/680.2, 680.3, 681-682
CPC A47B 45/00; A47B 57/00; A47B 47/02; A47B 47/05
